THE NORMAN PETERS CO., PHOTO-LITHO., WASHINGTON, D. C.

UNITED STATES PATENT OFFICE.

JOHN DONNELLY, OF BRANFORD, CONNECTICUT.

HACKSAW-FRAME.

1,277,879.

Specification of Letters Patent.

Patented Sept. 3, 1918.

Application filed February 21, 1918. Serial No. 218,529.

To all whom it may concern:

Be it known that I, JOHN DONNELLY, a citizen of the United States, residing at Branford, in the county of New Haven, 5 State of Connecticut, have invented a new and useful Hacksaw-Frame; and I do hereby declare the following to be a full, clear, and exact description of the invention, such as will enable others skilled in the art to 10 which it appertains to make and use the same.

This invention relates to an improved hacksaw frame.

An aim of this invention is to provide 15 a hacksaw frame involving simple, efficient and practical features of construction, and advantages over the hacksaw frame set forth, illustrated and claimed in the application of John Donnelly filed August 28, 20 1917, Serial No. 188,664 and allowed Sept. 27, 1917, and which has matured into patent dated 5th day of March, 1918, Patent No. 1,258,202.

One of the objects of the invention is the 25 provision of a hacksaw frame having means rendering the frame adjustable, whereby different lengths of blades may be held.

A further object of the invention is the provision of improved adjustable connections for the blade, whereby the blade may be held in a plane parallel with the frame, 30 or at right angles thereto.

Heretofore, it has been found that in adjusting hacksaw frames to suit the length 35 of blade desired, the end piece of the frame must necessarily be held in position by the hand of the operator, while attaching the blade, which renders the attaching of the blade awkward, as well as losing considerable time.

Consequently a further object of the invention is the provision of means for overcoming these disadvantages, and at the same time holding the end piece of the frame in 45 position, when once having been adjusted.

One of the features of the invention is the provision of an improved spring loop for preventing the displacement of one end of the saw blade after it has been once attached to the tightening member of the frame.

In practical fields the details of construction may necessitate alterations falling within the scope of what is claimed.

55 The invention comprises further features

and combination of parts as hereinafter set forth shown in the drawings and claimed.

In the drawings:

Figure 1 is a view in side elevation of the improved hack-saw frame constructed in 60 accordance with the invention.

Fig. 2 is a view in elevation and partly in section, more clearly showing the features of the invention.

Fig. 3 is a detail perspective view of one 65 end of the frame, showing the saw-tightening device and the spring loop or clip for preventing the displacement of one end of the saw blade.

Fig. 4 is a detail perspective view of the 70 adjustable end piece of the hack-saw frame.

Fig. 5 is a detail perspective view of the coupling or connecting member between one 75 end of the saw blade and the adjustable end piece of the frame.

Fig. 6 is a detail perspective view of the tightening and connecting member for the inner end of the saw blade.

Referring more especially to the drawings, 80 1 designates the hack saw frame, which in appearance resembles the general shape of frame of this kind. The frame comprises a bar bent or curved at 2, to form the back 3 and the inclined end piece 4 of the frame. The end of the inclined piece 4 terminates 85 in a lug 5 passing through a plate 6, and is battered or mashed as shown at 7, whereby the plate 6 is riveted to the end piece 4. This plate has a rectangular opening 8. A saw blade connecting and tightening member 9 90 rectangular in cross section engages and fits in the opening 8, whereby the same is prevented from turning. Although the member 9 is rectangular in cross section substantially it is provided with threads 10, which are engaged by the interior threads of the cylindrical bore of the sleeve or thimble 11, which is frictionally fitted in the hollow bore 12 of the handle 13, so that by adjusting the handle the tightening and connecting member 95 may be adjusted through the opening 8, for tightening the saw blade 14. A ferrule 15 is frictionally fitted on the end of the handle, that is adjacent the plate 6, thereby preventing splitting of the handle. The 100 tightening and connecting member 9 has an extension 16, the end portion of which has an angular cutaway portion 17, and extending transversely of the extremity of the extension 16 is a pin. This pin is frictionally 105 110

fitted in place, and one end protrudes beyond the flat face of the cutaway portion, so as to provide a lug 19, which is designed to engage an aperture 20 of one end of the saw-blade 14. The body of the extension 16 has a transverse opening 21, and 22 denotes a loop. This loop constructed from a single length of spring wire, the ends 23 and 24 of which extend toward each other, and are offset in parallelism. One end 23 fits the opening or aperture 21, thereby pivotally mounting the loop, while the end portion 24 engages the crotch 25 of said cutaway portion 17. Since the end portions are offset, as shown, the sides of the loop 22 are of different lengths, and owing to this particular construction the loop 22 has a spring action. The loop end 26 engages over the lug 19 and contacts with the saw blade, and holds the same securely connected to the extension detachably. The frame has an end piece 27, which is constructed U-shaped in cross section, consequently made of sheet metal. One end of the end piece 27 is provided with upstanding ears 28, which form integral parts of the upper ends of the side pieces of said end piece 27, and between which ears the back bar 3 of the hack-saw frame passes. The back 3 of the frame engages the shoulder 29 where the sheet metal end piece is bent upon itself, while the opposite edge of the back 3 engages the pin 30, which extends transversely of the ends of the ears 28. It is to be noted that the shoulder 29 and the transverse pin 30 are offset from each other so as to limit the end piece 27 in its angular position. However, since the shoulder 29 and the transverse pin 30 are offset in the manner illustrated, the back 3 is capable of movement between the shoulder and the pin 30, by first tilting the end piece 27 in the direction of the arrow *a*. For example after tilting the end piece as previously stated, but against the action of the spring 31 (which holds the shoulder in contact with the back 3) the back 3 may be moved between the pin 30 and the shoulder 29. The spring 31 is located in the channel 32 between the sides of the end piece 27. This spring is coiled about the transverse pin 33, and is bent at 34 to engage one edge of the back 3, while the portion 35 of the spring engages the crotch of the channel and holds the shoulder 29 against the back 3. The other end of the end piece 27 has an opening 36 in the transversely curved portion of said end piece 27, to receive the saw connecting member 37. The opposite walls of the U-shaped end piece 27 is provided with curved depressions 38, which conform to and receive the connecting member 37, so as to hold the connecting member 37 axially aligned with the saw-blade. The connecting member 37 has an angular cutaway portion 39, and projecting from the flat-face of the cut-

away portion is a forwardly inclined lug 40, to engage the aperture 41 of the forward end of the saw-blade 14. The lug 40 extends angularly forwardly, so as to prevent detachment of the blade. The lower ends of the forward edges of the sides of the end piece 27 have notches 42. One end of the connecting piece 27 is provided with transverse pins 43 and 44 extending at right angles to each other. To hold the saw blade 14 as illustrated, in a plane parallel with the back 3, the ends of the pin 44 are designed to engage the notches 42. In order to hold the blade 14 in a plane at right angles to the back 3, the ends of the pin 43 may engage the notches 42. To arrange the saw blade in a plane at right angles to the back 3, the connecting member 9 may be adjusted in the direction of the handle, until the annular groove 45 of the connecting member 9 registers with the rectangular opening 8, then the connecting member 9 may be given a partial or in fact a quarter turn, which will dispose the flat face 18 of the cutaway portion 17 in a plane at right angles to the back 3, in which case the saw blade may be held correspondingly. After adjusting the flat face 18 in this manner, the rectangular part of the connecting member 9 may then be reinserted in the opening 8.

The invention having been set forth what is claimed as new and useful is:

1. A hack-saw-end connector, said connector having a transverse aperture and a cutaway portion, a spring loop having long and short arms, the longer arm having a lateral extension engaging said aperture pivotally mounting said loop, the shorter arm having a lateral part engaging the crotch of the cutaway portion providing spring action for the loop.

2. The combination with a hack-saw-end connector having a face to engage the side of a saw blade and a pin projecting from said face, of a loop of wire or the like pivoted to said connector by one arm and having the other arm yieldingly engaging said connector to spring the loop toward the pin.

3. The combination with a hack-saw-end connector provided with a cutaway portion one face of which to engage one side of a saw blade, of a pin projecting laterally from said face and extending through the saw blade, and a wire loop having one of its arms pivotally connected to the connector, and its other arm provided with means yieldingly engaging the crotch of the cutaway portion to spring the loop toward and over the pin to clamp the saw blade in position.

4. The combination with a hack-saw-frame-back, of a hack-saw-end connector constructed from a piece of flat metal bent longitudinally upon itself to construct the connector U-shaped in cross section, corresponding ends of the sides of said U-shaped

connector having parallel extensions, a pin connecting said extensions, and between which pin and the crotch between the extensions and one end of the bend of the connector, said hack-saw-frame-back engages, a spring pivotally mounted between the sides of the U-shaped connector and having a portion bearing against said back to hold the connector in position on the back adjustable, the lower end of the connector adjacent the

bend having an opening, and a second saw blade connector adjustably and detachably engaging in said opening.

In testimony whereof I have signed my name to this specification in the presence of 15 two subscribing witnesses.

JOHN DONNELLY.
